United States Patent Office

Des. 204,613
Patented May 3, 1966

204,613

CLOCK

Edward H. Meisner, Dumont, N.J., and Jerold R. Peterson, Roselle, Ill., assignors to Sunbeam Corporation, Chicago, Ill., a corporation of Illinois

Filed July 12, 1965, Ser. No. 86,118

Term of patent 14 years

(Cl. D42—7)

FIG. 1 is a front elevational view of a clock embodying our new design;

FIG. 2 is a top plan view thereof; and

FIG. 3 is a sectional view taken on line 3—3 of FIG. 1.
We claim:

The ornamental design for a clock, as shown.
